DESIGN FOR A MEDALLION OR THE LIKE

Robert E. Pollock, Key West, Fla.

Application November 24, 1948, Serial No. 149,799

Term of patent 7 years

(Cl. D45—19)

To all whom it may concern:

Be it known that I, Robert E. Pollock, a citizen of the United States, residing at Key West, in the county of Monroe and State of Florida, have invented a new, original, and ornamental Design for a Medallion or the like, of which the following is a specification, reference being had to the accompanying drawing, forming a part thereof.

In the drawing:

Fig. 1 is a front elevational view of a medallion or the like, showing my new design;

Fig. 2 is a side elevational view looking in the direction of the line 2—2 of Fig. 1;

Fig. 3 is a bottom view looking in the direction of the line 3—3 of Fig. 1; and

Fig. 4 is another side elevational view looking in the direction of the line 4—4 of Fig. 1.

I claim:

The ornamental design for a medallion or the like, as shown.

ROBERT E. POLLOCK.
